J. STUMPF

VALVE GEAR FOR STEAM ENGINES

Filed Feb. 19, 1921

UNITED STATES PATENT OFFICE.

JOHANN STUMPF, OF BERLIN, GERMANY.

VALVE GEAR FOR STEAM ENGINES.

Application filed February 19, 1921. Serial No. 446,504.

The invention relates to improvements in valve gear for steam engines and the method of operating same. The object is to provide a method and means whereby the valve actuation is the resultant of the actuations of two elements rotating at different rates of angular speed, whereby a higher valve lift is secured, and whereby the adjustment of the relative rotative positions of said rotative elements may be utilized to vary the cut off.

In accordance with my copending application Serial No. 386,419, filed June 3, 1920, for steam engines using the movements of two rotating shafts, one rotating at double the angular speed of the crank shaft, and the other at crank shaft speed, it has been my practice to utilize the rotation of one shaft to render ineffective certain strokes of rotation of the other shaft, without in any way influencing the effective strokes.

By the method and means comprised in the present invention the two rotating elements are so correlated and the resulting movement utilized as to secure the same high valve lift as described in the above mentioned application, and by shifting the relative rotative position of one rotative element, with respect to the other, the cut-off can be regulated as required, while the beginning of the admission is kept constant.

The advantage of such control, is the possibility of securing, with engines working only with short cut-off, the rapid valve actuation and high lift desired for such short cut-off, or greatly increasing the possible length of cut-off in cases where great overload capacity is required. The former arrangement is especially adapted to power engines in dynamo plants, and particularly for uniflow engines, where very regular short cut-offs are required.

The latter arrangement is adapted to engines carrying high overloads, such as automobiles, rolling mill engines and engines for driving line shafts.

As convenient means for effecting the invention, I provide the rotating elements with cranks or eccentrics and mount the eccentric parts by a screw threaded engagement, so that their relative positions may be shifted for variations as to lift and advance on each other. This arrangement not only saves the side flanges, which render the construction difficult, but also these threaded sections, having oblique lateral faces as commonly known, causes the advantageous self-

stopping action which relieves the governor of back pressure.

The two rotating elements or shafts are preferably arranged in stepped relationship 60 beside the cylinder, and a double armed lever swinging on the lifting element or eccentric of one shaft is connected, as to one arm, with the variable lifting element of the other shaft, and as to the other arm, with the admission valve.

Referring to the drawings which illustrate merely by way of example a suitable embodiment of the invention;

Fig. 1 is a cross-section of a horizontal steam cylinder showing a valve and valve gear with double speed lay-shaft and single speed cut-out shaft.

Fig. 2 is a side elevation and a transverse diagrammatic elevation, on an enlarged 75 scale, showing the means for driving the first lay-shaft at two to one speed, the gear train to drive the second lay-shaft at engine speed.

Fig. 3 is a similar showing, except that 80 the first lay-shaft is driven at engine speed and the second lay-shaft at twice engine speed.

Similar numerals refer to similar parts throughout the several views.

The rotating elements or shafts 2 and 3 are arranged parallel with the cylinder 1, and in a plane above that of the other. Shaft 2 is provided with the fixed main eccentric 4. This eccentric is provided with 90 a screw threaded periphery, upon which is mounted, with normal threaded engagement, the eccentric 5. This eccentric 5 is relatively adjustable on eccentric 4, which adjustment is adapted to be controlled by any 95 form of shaft governor as at 15. The other shaft 3 is provided with an eccentric 7 rigid therewith. A two-armed lever 8, 9, is journaled on eccentric 7. Arm 8 is connected with the eccentric rod 10 of the double 100 or compound eccentric 4 and 5. The other arm 9 is connected with rod 11, which actuates the admission valve 12.

It will thus be seen that rod 11, is moved by the lever 8, 9, the fulcrum of which is the eccentric 7. The lever end 8 is actuated by the eccentric rod 10. If the lever end 8 is moved outwardly or away from shaft 2 and at the same time the fulcrum 7 is also moved outwardly away from the shaft 2, 110 there will be little or no movement of rod 11, depending upon the ratio of actuating

movements caused by the eccentrics 5 and 7. If however the fulcrum 7 is moved inwardly toward shaft 2, when lever end 8 is moved outwardly, the movement of the lever end 9 and consequently of the rod 11, is the resultant of said two eccentric actuated movements, which resultant movement depends upon the ratio of the extents of said two eccentric actuated movements. The "actuating direction" of movement of each eccentric, is the direction of movement of such eccentric which tends to cause the opening of the valve.

In the arrangement shown, for example in Fig. 2, the shaft 3 makes one-half revolution to one full revolution of shaft 2, so that with each alternate rotation of shaft 2 and eccentric 5, the valve opening effect of eccentric 5 is counteracted by the half rotation of eccentric 7; while the eccentric 7 coacts with the other revolutions of eccentric 5, both moving in actuating directions, which coaction gives valve opening movements greater than that due to either eccentric alone.

The driving gears 16 and 17, as shown in Fig. 2 are arranged to cause the rotation of shaft 2 at twice the angular speed of the crank shaft, and the train of gears 18, 19 and 20 causes the rotation of shaft 3 at the same speed as that of the crank shaft. In this event the lifts of the valves are particularly high, a maximum cut-off of 35% being possible, that is, on a 10% normal cut-off basis an overload of the engine to about three times its ordinary working capacity. Here the shaft governor has four times the power, as a result of its rotating at double speed.

On the other hand, by the arrangement shown in Fig. 3, the driving gears 16 and 17' are of the same diameter so that the lay-shaft 2 will rotate with the same velocity as the crank shaft and the relation of gears 18' and 20' is such that the cut-out shaft 3 will make double the number of rotations. In this way a maximum cut-off as high as 65% is attainable, in which event the lift is not as high as in the first form, but is still double that of the ordinary regulating arrangements, so that a single beat valve can still be used. With this arrangement the governor may run with the ordinary num-

ber of revolutions, but has not the exceedingly high lifting power of the first form. 55

What I claim is:—

1. Valve gear for steam engines comprising two eccentrics running at different angular speeds, and valve operating mechanism associated therewith, including a 60 rocking lever having as its fulcrum one of said eccentrics means for establishing operative relationship between said lever and the other eccentric, and means for communicating movement from said lever to the valve, 65 the elements having such operative relationship that the eccentrics will cooperate to give one valve opening movement with each rotation of the crank shaft, said valve opening movement being greater than that due to either eccentric alone.

2. Valve gear for steam engines comprising two eccentrics running at different angular speeds, and valve operating mechanism associated therewith, including a 75 rocking lever having as its fulcrum one of said eccentrics means for establishing operative relationship between said lever and the other eccentric, and means for communicating movement from said lever to the valve, 80 the elements having such operative relationship that the eccentrics will cooperate to give one valve opening movement with each rotation of the crank shaft, said valve opening movement being greater than that due to either eccentric alone, and a governor associated with one eccentric.

3. Valve gear for steam engines comprising two eccentrics, one running at crank 90 shaft speed and the other running at a multiple speed thereof and valve operating mechanism associated therewith, including a rocking lever having as its fulcrum one of said eccentrics means for establishing operative relationship between said lever and the other eccentric, and means for communicating movement from said lever to the valve, 95 the elements so related that the eccentrics will cooperate to give one valve opening movement only with each rotation of the 100 crank shaft, said valve opening movement being greater than that due to either eccentric alone.

In testimony that I claim the foregoing as my invention, I have signed my name.

JOHANN STUMPF.
